BEVERAGE COOLING DEVICE

Thomas L. Kuebler and Carl J. Schmock, Erie, Pa., assignors to Uniflow Manufacturing Company, Erie, Pa., a corporation of Pennsylvania

Application February 8, 1954, Serial No. 408,809

7 Claims. (Cl. 62—185)

This invention relates to refrigeration apparatus and more particularly to apparatus for cooling beverages to maintain the beverage flowing from a container to a discharge spigot at as nearly an optimum temperature as practicable.

Numerous types of devices have been developed and used to cool beverages and maintain them at proper serving temperatures; however, they have had various disadvantages and faults in their operation. One method of direct expansion of refrigerant in close proximity to the beverage pipes has, among other faults, the undesirable effect of shock cooling of the beverage and of occasional freezing of the beverage. Another method of cooling the beverage pipes with refrigerated air has the disadvantage of limited capacity under heavy heat load conditions and poor temperature control under varying heat loads. Another method of cooling the beverage with refrigerated liquid coolant has also had problems of temperature control under varying loads and, in some types, limited capacity under peak loads. One type using continuously circulating liquid coolant has pronounced problems of temperature control and limited capacity. Another type with intermittent circulation of liquid coolant overcomes these problems to some extent; however, it loses the advantages of continuous circulation; namely, more uniform temperature of the liquid coolant throughout all parts of the system.

As can be seen from the above brief resume, a major problem in cooling and maintaining a beverage at the proper temperature is in the necessity for close control of the temperature of the cooling medium throughout the system, particularly during times of varying loads. This invention solves this problem and lends other advantages as will be apparent.

It is, accordingly, an object of this invention to overcome the above and other disadvantages in prior cooling equipment and more particularly it is an object to provide a beverage cooling device which is simple in construction, economical in manufacture, and efficient in use.

Another object of the invention is to provide a beverage cooling device wherein a valve causes the circulating liquid to bypass a refrigeration coil when the system reaches equilibrium and the valve directs the flow of circulating liquid over the refrigeration coil when the system is operated under load.

A further object of the invention is to provide a beverage cooling device wherein the beverage cooling liquid can be circulated through a storage room to keep the storage room in cooled condition.

A further object of the invention is to provide a cooling device for a beverage which will hold the beverage at a substantially constant temperature.

With the above and other objects in view, the present invention consists of the combination and arrangement of parts hereinafter more fully described, illustrated in the accompanying drawings, and more particularly pointed out in the appended claims, it being understood that changes may be made in the form, size, proportions, and

2

minor details of construction without departing from the spirit or sacrificing any of the advantages of the invention.

In the drawings:

Fig. 1 is a cross sectional view of a cooling unit for use in connection with our invention;

Fig. 2 is a top view of the cooler shown in Fig. 1;

Fig. 3 is a detailed cross sectional view of a modulating valve;

Fig. 4 is a cross sectional view of a beverage storage room;

Fig. 5 is a side view of the cooling equipment;

Fig. 6 is a broken away view of another embodiment of the invention; and

Fig. 7 is a cross sectional view of still another embodiment of the invention viewed from the top thereof.

Now with more specific reference to the drawings, we show a cooling unit 1 having a lower liquid bath compartment 2 and an upper liquid bath compartment 3 separated from each other by a baffle 4. The baffle 4 does not necessarily form a liquid tight partition between the upper and lower liquid baths 3 and 2. The baffle 4 has an aperture 5 therethrough through which the cold liquid outlet pipe 6 extends. The upper and lower liquid baths 3 and 2 are contained in a tank 7 surrounded by insulating material 8 and preferably supported above the floor by the stand 9.

If it were desired to operate the cooler as a unit, beverage containers could be stored in the space 10 below the liquid tank; however, in the present disclosure, we show the cooling unit shown in Fig. 1 adapted to be connected to a separate beverage storage compartment such as that shown in Fig. 4.

Preferably located in the upper liquid bath 3, we provide the circulating pump 12 having the return pipe 13 connected thereto at 14 and discharging through pipe 15 into the modulating valve 16 and from the modulating valve 16 to the warm liquid outlet pipe 17 which extends through the baffle 4 at 18 and discharges in the lower liquid bath 2 at 19. A refrigeration coil 20 connected to a suitable refrigeration unit, for example, a compressor operating on a conventional refrigeration cycle, is disposed in the lower liquid bath 2.

The cooling unit is connected to the storage compartment shown in Fig. 4 by the conduit or heat transfer device 21 having insulating material 22 extending therearound and having a hollow portion 23 extending therethrough. The conduit 21 terminates in header 66. The conduit 21 preferably has a liquid proof liner 24 through which the liquid from the cooling unit flows and preferably through which the liquid return pipe 13 extends and, likewise, the beverage pipe or pipes 26 extend therethrough connected to faucet 67.

The storage compartment shown in Fig. 4 is made up of the insulated wall 28 which encloses the storage room and is adapted to store containers of beverage such as container 29. A cooling device 30 is supported on a platform 31 in the storage chamber and a fan 32 circulates air through the device 30 to keep the storage room at a temperature below the spoiling temperature of the beverage.

The preferred type of valve 16 is made up of the body 34 having the bellows 35 therein and having the valve member 36 connected to the bellows 35 by means of shaft 37. As warm liquid entering the inlet 38 engages the bellows 35, the bellows 35 expands, urging the valve member 36 toward the direct circulation outlet 40 and allowing more liquid to flow over the bellows 35 through the fluid outlet 39 which is connected to the pipe 17 to circulate more liquid over the cooling coils 20. As the temperature of the liquid circulating in the system decreases, the bellows 35 will be cooled, drawing the valve member 36 toward the partition 41, thereby

restricting the flow of liquid through the opening 39 and allowing more liquid to flow out of the direct circulation outlet 40 and into the area above the baffle 4. In some applications, it may be desirable to substitute a thermostatically controlled solenoid valve or a snap action temperature control valve between the pipes 15 and 17 instead of the valve shown in Fig. 3.

When the system has been operating at equilibrium, that is, when the beverage has been cooled and the system has reached the uniform temperature, the liquid over the bellows 35 will be cool and will cause the valve member 36 to move toward the end 39 and most of the liquid will be discharged from the outlet 40 into the upper liquid bath 3 and circulates from the upper liquid bath 3 through hollow 23 of the conduit 21 and along the beverage pipe 26 through the inlet pipe 44 to the cooler through the cooling device 30 which may be of a fin tube or other suitable design to the return tube 45 and through the return pipe 13 to the pump 12. Thus, when the device is operated at practically no load or when no beverage is being drawn, practically no liquid will circulate over the refrigeration coil 29 but will circulate from the pump 12 back to the conduit 21. When beverage is being drawn or when the system has not reached equilibrium, the liquid in the hollow 23 of the conduit 21 will be somewhat warmed by the flow of warm beverage therethrough or otherwise. Therefore, the liquid returning through the return pipe 13 will cause the bellows 35 to expand, causing the valve member 36 to move to restrict the opening 40 and allow more flow through outlet 19 over the refrigeration coils 29 through the inlet 45 through the cold liquid pipe 6 and then through the conduit 21. Since the valve 16 operates gradually, some liquid may flow over the coils and some bypassed as the temperature changes. As the system drops in temperature approaching equilibrium, the action of the cooler liquid on the bellows 35 will cause the modulating valve 16 to cause the flow of liquid to bypass the cooling coil and to directly circulate through the system. We have discovered that a number of liquids, for example, water, brine, or any anti-freeze liquid or combination will work satisfactorily in this system. The pipes 44 and 45 could be deleted if it were not desired to cool the storage chamber.

To carry this out, we show another form of the conduit end in Fig. 6 wherein we provide a conduit for use without the cooling device 30. Instead of bringing the pipe 13 through the header 66, we allow the pipe 213 to terminate in the header 266 so that liquid is drawn through the conduit 224 into the header 266 and into the end 270 of the pipe 213. Beverage is drawn through the pipe 226 in the same manner that it is drawn through the pipe 26 in Fig. 1.

In Fig. 7, we show another embodiment of the invention wherein the upper liquid bath is eliminated. When beverage is being drawn, the liquid in the pipe 113 will be warmed and will cause the valve 116 to direct the warm liquid through outlet 139 and pipe 117 through the opening 119 into the refrigerated bath 102. Cold liquid will be picked up through the cold liquid outlet pipe 106 and will flow through T 180 and pipe 181 into the conduit 121. Beverage will be drawn through pipe 126 and faucet 167. When the system is in equilibrium, valve 116 will direct liquid through outlet 140 directly into T 180 and pipe 181 into the conduit 121.

If it is desired to provide more thermal inertia in the system and increase peak load capacity, ice or solidified liquid could be formed around the cooling coils by running the refrigeration for a period of time after the system reached equilibrium.

In the foregoing specification, we have set forth the invention in its preferred practical forms but we are aware that the structure shown is capable of modification within a range of equivalents without departing

from the invention which is to be understood is broadly novel as is commensurate with the appended claims.

The embodiments of the invention in which an exclusive property or privilege is claimed are defined as follows:

1. A beverage cooling device comprising a cooling unit containing a refrigerated compartment, a conduit, a beverage pipe, a pump, a temperature responsive valve, a liquid, said beverage pipe passing through said conduit, means connecting said pump in flow relationship to said conduit, said pump circulating said liquid through said connecting means and said conduit, means connecting said valve in the path of flow of said liquid, flow line means connecting said valve to said refrigerated compartment, and means connecting said refrigerated compartment in flow relationship to said conduit, said valve having means directing said liquid through said refrigerated compartment when the temperature of said liquid passing through said valve rises above a predetermined value, said valve means allowing said liquid to circulate through said conduit without passing through said refrigerated compartment when the temperature of said liquid drops to the predetermined value.

2. The beverage cooling device recited in claim 1 wherein said valve is a modulating valve, said valve means directs a small portion of liquid through said refrigerated compartment when the temperature of liquid flowing through said valve increases slightly, said valve means directs a large portion of said liquid through said refrigerated compartment when the temperature of said liquid flowing through said valve changes a large amount.

3. In combination, a beverage cooling and dispensing unit comprising a cooling unit containing a refrigerated compartment, a liquid bath compartment, a conduit, a beverage pipe, a pump, a temperature responsive valve, and a liquid; said conduit being connected in flow relationship to said liquid bath compartment, said beverage pipe passing through said conduit and said liquid bath compartment to a tap disposed through the wall of said liquid bath compartment, means connecting said pump in flow relationship to said conduit and said liquid bath compartment, means connecting said valve in the path of flow of said liquid, means connecting said valve in flow relationship to said refrigerated compartment, and means connecting said refrigerated compartment in flow relationship to said liquid bath compartment, said valve directing said liquid through said refrigerated compartment when the temperature of said liquid passing through said valve rises above a predetermined value, said valve allowing said liquid to circulate through said conduit without passing through said refrigerated compartment when the temperature of said liquid drops to the predetermined value.

4. The combination recited in claim 3 wherein said valve is a modulating valve having means to direct a small portion of liquid through said refrigerated compartment when the temperature of liquid flowing through said valve increases slightly and having means to direct a large portion of said liquid through said refrigerated compartment when the temperature of said liquid flowing through said valve changes a large amount.

5. The beverage cooling device recited in claim 1 wherein a storage compartment for beverage is provided, said conduit communicating from said cooling unit to said beverage storage compartment, said beverage pipe passing from said storage compartment through said conduit to a tap.

6. The beverage cooling device recited in claim 5 wherein a cooling device is disposed in said storage compartment with liquid conducting means connecting said cooling device to said conduit, said liquid being circulated through said cooling device whereby said storage compartment is cooled.

7. The beverage cooling device recited in claim 6

wherein said cooling device comprises a heat exchanger and a fan for circulating air therethrough.
